TABLE LEAF LIFTING DEVICE

Albert R. De Burgh, Portland, Oreg.

Application July 21, 1931. Serial No. 552,203
Renewed February 17, 1933

5 Claims. (Cl. 45—112)

This invention relates generally to extension tables, and particularly to those having extra leaves which are raised and lowered.

The main object of this invention is the provision of an automatic leaf operating device which will not repeat, that is, one in which the leaf will be raised when the table is pulled apart once any distance greater than needed for the leaf, and held in that position until the top is closed against the inserted leaf, and in the second opening operation of the table top it will permit the extra leaf to descend in order that the table may be restored to its contracted position.

The second object is to construct a leaf-lifting mechanism which will be simple to manufacture and not easily rendered inoperative.

These, and other objects, will become more apparent from the specification following as illustrated in the accompanying drawing, in which:

20 Fig. 1 is a side elevation of the device.

Fig. 2 is a vertical section taken along the line 2—2 in Fig. 1.

Fig. 3 is a broken section taken along the line 3—3 in Fig. 1.

25 Fig. 4 is a perspective view of the bracket.

Fig. 5 is a longitudinal vertical section through a portion of a table top showing the table pulled apart getting ready for the leaf-raising operation.

Fig. 6 is an elevation showing the means for 30 preventing the repetition of the lifting operation.

Similar numbers of reference refer to similar parts throughout the several views.

Referring in detail to the drawing, in order to simplify the illustration there is shown only those 35 portions of a table which are intimately connected with the invention, namely the top portion 10 to which is attached a slide 11 above which is mounted an extra leaf 12. The extra leaf has attached thereto on its under side a pair of brackets 13 from the side of which projects a horizontal pin 14, which may be solid or in roller form as desired. On the side of each slide 11 is secured a curved plate 15, each end of which is secured to the slide 11 by means of a screw 16. 40 The plate 15 is secured to the slide 11 so that the end 17 will be nearer its upper side and the end 18 will be nearer its lower side.

The end 18 is provided with a laterally turned flange 19 which is in the form of a half circle 50 and terminates in a horizontal flange 20 which is tangent to the main flange at its lower side. The upper end 17 is also provided with a semi-circular flange 21 which is tangent to the horizontal flange 22 which extends in the direction 55 of the flange 20, although in a higher plane, and

then turns abruptly downwardly at an angle of about 45 degrees from the horizontal. The portion 23 joins with the portion 22 in a tangent curve 24.

Between the ends 17 and 18 is pivotally mounted 60 a three-arm lever 25 by means of a shouldered rivet 26. The lever 25 is kept from engaging the plate 15 by means of the washer 27. An arm 28 on the lever 25 is sufficiently long and heavy to cause the face 29 of this arm to rest 65 normally against the flange 20, where as the cam face 30 forms the leaf-lifting side of the arm 28.

A second and shorter arm 31 is opposite the arm 28 and engages the curved flange portion 24 when the arm 28 is raised, forming a bridge between the rivet 26 and the flange 22. The third arm 32 is still shorter and points downward on the same side of the vertical center of the rivet 26 as is the arm 21, and its function is to prevent 70 repeating.

The operation of the device is as follows: Bearing in mind that the top portion 10 is capable of horizontal slidable movement on its slides 11 and that the leaf portion 12 is capable only of vertical movement on its pins 33, which pass slidably 75 through the cross tie 34, it will be seen that if the table is in a contracted position and the top portions 10 are pulled apart there will be a relative movement between the pin 14 and the arm 25.

It will be assumed that the table is so manipulated that no horizontal movement will be imparted to the leaf 12. A pulling movement on the top 10 will cause the lever 25 to move toward the pin 14 over which passes the arm 32, and if the top 10 is pulled sufficiently far it will cause the arm 28 to be raised (as shown in Fig. 5), and when it has passed the pin 14 the arm 28 will again fall under its own weight, trapping the pin 14 between the semi-circular flange 19 and its own face 30. When the table top portions 10 are again moved toward each other the pin 14, which is now in contact with the face 30, is raised until it rides upon the top side of the arm 31, causing the arm 31 to be depressed into engagement with the curved flange portion 24 80 from which the pin 14 descends upon the flange 22 and again releasing the arm 28 permitting it to descend to the position shown in Fig. 1.

It will be understood that the table is now in an extended position tightly closed upon the extra leaf. If it is desired to lower this leaf the top portions 10 are pulled apart as before, but this time the pin 14 comes into contact with the under side of the arm 31. The opening movement of the portions 10 is now limited by the 85 arm 32 (as shown in Fig. 6) which holds the 90

moving parts against the pin 14. The only other movement which the operator can make is to close the table, which he does by reason of the fact that the extra leaf is now on the under side thereof.

5 From the foregoing it can be seen that there is provided a fully automatic table which is simple to construct and incapable of repeating in the sense referred to in the second paragraph of the specification.

10 I claim:

1. A table leaf lifting device consisting of a rocker arm adapted to be pivotally mounted on a table slide, said arm having a stop for holding a top portion thereof in an inclined position, a shelf forming a relatively stationary extension for the upper portion of said arm, a leaf supporting pin adapted to ride over the top of said arm and rest upon said shelf in a manner to raise and sustain a leaf in an elevated position or to 20 pass under said rocker arm in a manner to permit said leaf to lower for storage purposes.

2. A table leaf lifting device consisting of an inclined rock lever adapted to swing in a vertical plane having one portion thereof above its pivotal point and the other portion thereof below its pivotal point, stop means for holding said rock lever to a limited movement in each direction, a relatively stationary extension for the upper portion of said rock lever, a second stop means across the path between the upper portion of said rock lever and said extension, and a pin having supporting means for attaching same to the under side of a table leaf, said pin being adapted to ride upon the upper side of said inclined arm over the top thereof and rest upon said extension or to ride off of said extension under the upper end of said arm against said second stop.

3. A table leaf lifting device consisting of a rocker arm having an inclined top, side portions

of which extend above and below its pivotal point, a repeat prevention arm projecting from the under side of said rocker arm, an extension for the upper end of said rocker arm having its end nearest said rocker arm downturned toward said repeat prevention arm, and a vertically movable pin adapted to ride on the top side of said rocker arm or to pass beneath the under side thereof.

4. In a table the combination of horizontally 80
slidable top portions and an interposed vertically 85
movable leaf portion, said leaf portion having a 90
bracket secured to the under side thereof including 95
a horizontal pin member attached to the bracket, said 100
slidable top portions having slides attached thereto extending under said interposed leaf, a rocker arm pivotally mounted on the side 105
of a slide adapted to receive horizontal movement 110
therefrom, said rocker arm having its upper side inclined from the horizontal, an extension 115
for the upper end of said inclined arm forming a stop therefor, and stop means for limiting the downward movement of the lower end of 120
said arm.

5. An elevator for extension leaf tables 100
consisting of a horizontally movable member, a rock- 105
er arm pivotally mounted on said movable member 110
adapted to swing in a vertical plane, said 115
rocker arm having three extensions pivoted about 120
an intermediate point two of said extensions lying 125
diametrically opposite each other and the 130
third extending one side thereof normal to the 135
line connecting said two first mentioned exten- 140
sions, a bracket adapted to be secured to the under 145
side of an extra leaf, said bracket having a 150
